REFLECTIVE ROADWAY MARKER

Howard A. Schaefer, Lancaster, Ohio, assignor to Anchor Hocking Corporation, Lancaster, Ohio

Filed Sept. 21, 1972, Ser. No. 290,820

Term of patent 14 years

Int. Cl. D29—02

U.S. Cl. D72—1 J

Fig. 1.

Fig. 2.

Fig. 4.

Fig. 3.

Fig. 5.

FIG. 1 is a top plan view of a reflective roadway marker showing my new design;

FIGS. 2—4 are side elevation, bottom plan and front elevation views of the reflective roadway marker shown in FIG. 1; and

FIG. 5 is a cross-sectional view taken through FIG. 1 along the line 5—5.

I claim:

The ornamental design for a reflective roadway marker, substantially as shown and described.
